UNITED STATES PATENT OFFICE.

EDWIN H. SADLER AND ERNEST L. HALL, OF HUNTINGTON PARK, CALIFORNIA.

SUPPORTING DEVICE FOR AUTOMOBILES.

1,297,916.

Specification of Letters Patent. Patented Mar. 18, 1919.

Application filed September 21, 1918. Serial No. 255,155.

To all whom it may concern:

Be it known that we, EDWIN H. SADLER and ERNEST L. HALL, citizens of the United States, residing at Huntington Park, in the county of Los Angeles and State of California, have invented new and useful Improvements in Supporting Devices for Automobiles, of which the following is a specification.

10 This invention relates to new and useful improvements in supporting devices for automobiles and the principal object of the invention is to provide means for lifting the wheels of the automobile from the floor of

15 the garage. Another object of the invention is to provide means whereby the momentum of the automobile will operate means to raise the wheels off the ground.

20 Another object of the invention is to provide for lowering the rear wheels, to provide traction, for releasing the parts from the lifting means.

The invention also consists in certain 25 other features of construction and in the combination and arrangement of the several parts, to be hereinafter fully described, illustrated in the accompanying drawings and specifically pointed out in the appended claims.

30 In describing our invention in detail, reference will be had to the accompanying drawings wherein like characters denote like or corresponding parts throughout the several views, and in which:—

Figure 1 is a plan view of the invention.

Fig. 2 is a side elevation.

Fig. 3 is a side view showing the lifting means for the rear blocks in inoperation

40 position.

Fig. 4 is a longitudinal section.

Fig. 5 is a cross section on line 5—5 of Fig. 3.

Fig. 6 is a section on line 6—6 of Fig. 3.

45 In these views 1 indicates a pair of supporting beams, on which is located a pair of front inclined blocks 2 and a pair of rear inclined blocks 3. The inclination of the front edges of these blocks is greater than that of the rear edges. The rear blocks are provided with substantially flat portions at their apexes. On each of the front blocks is slidably mounted an axle engaging member 4, which engages the inclined edge

50 of the block. An angle iron 5 is secured to

the upper edge of this member. A spring 6 normally holds the member at the rear or lower part of the inclined edge of the block. If desired, the member may be connected with the block by the tongue and 60 groove 7.

8 indicates the rear axle engaging member, one of which is located on each of the rear blocks 3. These members are of substantially U shape, as shown, so as to accommodate the truss rod B of the automobile, the rear axle of which is indicated at A. The ends of the U are so spaced as to receive the axle with the part thereof resting on each end. The members 8 are 70 connected by links 9 to a sliding frame 10. This frame is connected with the blocks 3 by the tongue and groove connections 11. As shown, the links 9 have their ends pivoted to the members 8 and the frame and 75 springs 12 connect said links, intermediate their ends, with said frame.

13 indicates a bar having one end connected with the sliding frame 10 and its other end extending between the front 80 blocks 2. A guide bar 14 is connected with the bar 13 and this guide bar is suitably supported. The front end of the bar 13 is provided with slots 15 and a bracket 16 is slidably connected with the bar 13 by 85 means of the bolts 17 passing through said slots. The bracket is normally held in its rearmost position by means of the spring 18. The bracket is provided with an upward extension 19, which is provided with 90 a vertical bore 20. The bore receives the end of a rod 21 which is normally held in the upper end of said bore by spring 22. This rod is provided with a bent upper end as shown. 95

The rod 21 extends high enough to be struck by the front axle, indicated at C, of the automobile. The further movement of the automobile will cause the bracket to move forwardly and this action will cause 100 the bar 13 to pull the sliding frame forwardly so as to force the members 8 up the inclined edges of the blocks 3. The parts are so positioned that as the automobile moves forward and the members 8 move up the incline the truss rods will enter the space between the legs of the members 8 and said members will engage the rear axles near the end of their movement so as to 105 force the rear wheels off the floor when the 110

members reach the end of their movement and are resting on the flat portions. At about the time the front axle strikes the rod 21 it will also come in contact with the 5 front members 4 so that the momentum of the automobile will cause said members to slide up the inclined blocks and thus lift the front wheels off the floor.

The rear members 3 are vertically movable 10 by means of a pair of levers 24 which are pivoted to the lower part of each of the members 3 by the pins 25. These pins 25 pass entirely through the member and short levers 26 are secured to the pins at the other 15 side of the members. The upper parts of the levers 24 are slotted as at 27 and these slots are engaged by pins 28 carried by links 29 which have their ends pivoted as at 30 to a plate 31 secured to the central part of the 20 member 3. This plate is provided with a slot 32 and braces 33 pivoted to the links 29 have their ends pivoted together by a pin 34 which engages said slots. Springs 35 connect the upper parts of the levers 24 with the 25 member 3 and said springs tend to hold the levers in raised position so as to hold the members in their uppermost positions. The links 29 are of such a length that the levers 24 are held at a slight incline to the bottom 30 of the blocks 3, so that the weight of the automobile tends to tilt the levers and permit the blocks to move to their lowest position. The parts are held in this position by means of spring catches 36 carried by the 35 members 3 and engaging the levers. These catches are operated from any desired point by means of the cables 37.

It will thus be seen that when it is desired 40 to remove the automobile from the device it is simply necessary to withdraw the catches by pulling the cables 37. This action will allow the weight of the car to lower the members 3, by causing the levers to rock on their pivots, so that the rear wheels will come 45 in contact with the floor. Then, by starting the motor, the automobile may be backed off the device. In this action the parts will be returned to normal position by the movement of the automobile and the springs. If it is 50 desired to run forward, instead of backward, the forward movement of the automobile will push the sliding member over the highest parts of the blocks and down the front inclined edges of the blocks so that the axle 55 will be released the same as if the automobile was backed. As the front axle moves downwardly it will engage the bent end of rod 21 and force said rod downwardly out of its way.

60 The rear blocks 3 are guided in their vertical movement by the pins 38 engaging the recesses 39 formed in said blocks.

Bumpers 40 are located adjacent the front blocks against which the front wheels of the 65 automobile will strike to prevent the car

from passing over the device. These bumpers must be removed if the automobile is to be moved forwardly off the device.

If it is desired to raise the wheels on one side only of the machine, this can be done by 70 removing the sliding members on the opposite side of the device.

It will be seen that the rear blocks are of less height than the front blocks so that the front axle can pass over the rear blocks. Of 75 course, it will be understood, that the automobile may be backed upon the device but to do this the blocks must be reversed.

After an automobile leaves the device the parts are in a position to receive another 80 automobile.

It is thought from the foregoing description that the advantages and novel features of our invention will be readily apparent.

We desire it to be understood that we may 85 make changes in the construction and in the combination and arrangement of the several parts, provided that such changes fall within the scope of the appended claims.

We claim as our invention:

1. A device of the class described, comprising a pair of front and rear blocks having their upper edges inclined both forwardly and rearwardly, axle engaging members slidably engaging said blocks, a member located between the front blocks and having a part thereon adapted to be struck by the front axle, means permitting the said part to be depressed to permit the automobile to pass down the forwardly inclined edges of the blocks, means for connecting said member with the axle engaging members of the rear blocks, and means for moving said rear blocks vertically. 90

2. A device of the class described, comprising a pair of front and rear blocks having their upper edges inclined both forwardly and rearwardly, the apexes of the rear blocks being flat, axle engaging members slidably engaging said blocks, a member located between the front blocks and having a part thereon adapted to be struck by the front axle, means permitting the said part to be depressed to permit the automobile to pass down the forwardly inclined edges of the blocks, means for connecting said member with the axle engaging members on the rear blocks, and means for moving said rear blocks vertically. 100

3. A device of the class described, comprising a pair of front and rear inclined blocks, axle engaging members slidably engaging said blocks, a frame slidably connected with the rear blocks, links connecting said frame with the axle engaging members on the rear blocks, a bar connected to said frame and extending forwardly between the front blocks, a bracket slidably connected with said end of said bar and having a part adapted to be struck by part of the automo- 110 120 125 130

bile, and a spring connecting said bracket with the bar.

4. A device of the class described comprising a pair of front and rear inclined blocks, axle engaging members slidingly engaging said blocks, a frame slidingly connected with the rear blocks, links connecting said frame with the axle engaging members on the rear blocks, a bar connected with said frame and extending forwardly between the front blocks, a bracket connected with said end of said bar and a vertically movable member in said bracket adapted to be struck by a part of the automobile.
5. A device of the class described comprising a pair of front and rear inclined blocks, axle engaging members slidingly en-

gaging said blocks and adapted to be forced up the inclines by the momentum of the automobile and means for moving said rear blocks vertically, said means comprising a pair of pivoted levers having their upper parts slotted, a pair of links having their outer ends pivoted in said slots, a plate carried by the block and having a slot therein, 25 the inner ends of said links being pivoted to said plate, braces having their inner ends pivoted in the slot in the plate and their outer ends pivoted to the links and catches for holding the levers in operative position. 30

In testimony whereof we affix our signatures.

EDWIN H. SADLER.
ERNEST L. HALL.
